CLAIM

The ornamental design for an oral irrigator, as shown and described.

DESCRIPTION

FIG. 1 is a front perspective view of an oral irrigator showing my new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is an enlarged view of a portion indicated with "9" in FIG. 2.

The evenly dashed broken lines illustrate portions of the oral irrigator that form no part of the claimed design. The dot-dash lines illustrate the border of the enlarged detailed views and form no part of the claimed design.
